UNITED STATES PATENT OFFICE.

JOSEPH M. SEAWELL, OF RICHMOND, VIRGINIA.

DESIGN FOR A FOB.

No. 38,806.

Specification for Design.

Patented Sept. 17, 1907.

Application filed February 28, 1907. Serial No. 359,037. Term of patent 3½ years.

To all whom it may concern:

Be it known that I, JOSEPH M. SEAWELL, a citizen of the United States, residing at Richmond, county of Henrico, State of Virginia, have invented a new and original Design for Fobs, of which the following is a specification, reference being had to the accompanying drawing, in which—

The figure is a front view of my design.

I claim—

The ornamental design for a fob, as shown.

JOSEPH M. SEAWELL.
